WASHING MACHINE

William Joseph Byrne, Indianapolis, Ind.

Application May 31, 1930. Serial No. 458,624

24 Claims. (Cl. 68--18)

This invention relates to the art of washing machines particularly of the type adapted to be used in commercial dry cleaning and laundry establishments, and this application is a continuation in part of my prior application for U. S. Letters Patent filed November 22, 1929, Ser. No. 409,108.

Important objects of my invention reside in providing a structure wherein the outer hull may be revolved to vary the elevation of the door opening therein from the floor; wherein an unloading platform may be readily inserted from either of two doors in the inner cylinder; and wherein a safety blast relief is automatically provided prior to opening of a door in the hull.

Other objects reside in the various unique combinations of elements permitting a simplified structure capable of being produced at a relatively low cost and of being operated with the minimum expenditure of effort upon the part of the operator. These and additional objects will be apparent in the following description of the invention as illustrated in the accompanying drawings, in which

25 Fig. 1 is a top plan view of a machine embodying my invention;

Fig. 2, a front elevation;

Fig. 3, a right hand end elevation;

Fig. 4, a left hand end elevation;

30 Fig. 5, a detail of the hull shifting mechanism in right hand elevation;

Fig. 6, a fragmentary vertical transverse section through the hull, with the doors open;

Fig. 7, a vertical transverse section through the 35 cylinder only with the doors closed;

Fig. 8, a horizontal longitudinal section through the cylinder on the line 8—8 in Fig. 7;

Fig. 9, a fragmentary front elevation of a modified form of fluid intake piping; and

40 Fig. 10, a left hand side elevation of the structure shown in Fig. 9.

Like characters of reference indicate like parts throughout the several views in the drawings.

I form the two symmetrical supporting standards 15 and 16 to have essentially an inclined A shape, built up from structural channel iron, each having a vertical rear leg 17, an inclined front leg 18 welded to the rear leg at the top, a horizontal lower tie 19, and the central brace 20, extending at right angles from the front leg 18 downwardly to abut the rear leg 17. The front leg 18 is preferably sloped toward and united with the rear leg 17 at an angle of thirty degrees, whereby only sixty and ninety degree cuts are required on the ends of the tie 19 and brace 20. Longitudinal members 21 and 22 tie the standards together near their lower ends.

On the outer faces of the front legs 18 of the standards are fixed the bearing plates 23 and 24 directly over the braces 20, which bearings ro-

tatably support the trunnions 25 and 26 of the hull 27, the hull being normally free to revolve therebetween. To retain the hull at the desired point of rotation, I provide bands of strap iron, 28 and 29, one at each end, to pass circumferentially therearound to have their rear ends secured to the member 22 and their front ends to the upper ends of the links 30 which are pivotally secured to the member 21, Figs. 3 and 4, and a shaft 31, rockably supported between the front legs 18, has cams 32 adjacent the links 30 and a forwardly extending arm 33, whereby downward pressure on the arm 33 will rock the cams 32 against the links 30 to swing them rearwardly and hence pull downwardly on the bands 28 and 29 to tighten them against the hull 27.

Cleaning fluid is supplied to the hull 27 through a fitting 34 fixed on the back of the standard 15 from which a length of flexible hose 35 extends to an L 36 which screw-threadedly fits into the 80 wall of the hull 27. The fluid may be drained from the hull 27 through the L 37 in the bottom of the hull 27, through the flexible hose 38, the fitting 39 fixed to the tie 19, the valve 40, and out the pipe 41. To prevent overflow of the 85 hull, a by-pass 42 is provided around the valve 40, Fig. 4, in the form of the vertical pipes 43 and 44 with the horizontal connection 45 therebetween. By providing the flexible hose 35 and 38, the hull 27 may be rocked through an appreciable circumferential travel before being limited by the hose lengths.

A cylinder 46 is carried within the hull 27 and has shafts 47 and 48 extending longitudinally through the hull trunnions 25 and 26 to be rockably carried in the bearings 49 and 50 mounted on the legs 18 of the standards 15 and 16 whereby the cylinder may be revolved within the hull 27 independently of rotation of the hull. The shaft 48 extends beyond the bearing 50 and has a spur gear 51 fixed thereon, which gear meshes with the idler gear 52. A drive gear 53 meshes with the idler gear 52 and is fixed on the end of the shaft 54 carrying the driving pulleys 55. A housing 56 is provided to enclose the gearing. 105 A crank shaft 57 is rotatably supported on the standard 16 to be fixed longitudinally thereover. On the inner end of the shaft 57 is a gear 58 in constant mesh with a rack gear 59 fixed on the end of the hull 27. On the outer end of the 110 shaft 57, is carried a hub 61 with a gear 62 on the inner end and a crank 63 on the outer end.

An annular slot 64 is formed in the hub outside of the gear 62 and a pin 65 normally extends to within the slot to prevent longitudinal movement of the hub 61 along the shaft 57. In that position the gear 62 is out of mesh with the gear 51. The outer end of the shaft 57 has a pin 66 extending diametrically therethrough, the ends of which are engaged in slots across the 120

outer end of the hub 61. Thus, upon rotation of the crank 63, with the pin 65 entered in the slot 64, the shaft 57 is revolved through the pin 66 to revolve the gear 58, which in turn causes the hull 27 to revolve, upon release of the bands 28 and 29.

Upon pulling the pin 65 out of the slot 64, the hub 61 may be shifted inwardly along the shaft 57 to mesh the gear 62 with the gear 51, whereupon, revolving the crank 63, will revolve the cylinder 46 within the hull, without moving the hull. A plate 67, fixed on the outer end of the shaft 48 has a double ended arrow 68 painted thereon to indicate the positions of the doors 69 and 70 in the cylinder, so that, upon registering either head of that arrow 68 with the fixed point 71 on the housing 56, either door in the cylinder will be properly presented for unloading the cylinder as will hereinafter be explained.

The hull 27 is entirely closed save for an opening 72 for a length circumferentially therearound, the normal position of which opening is on the upper side of the hull. Arms 73 and 74 are hinged respectively to the upper ends of the standards 15 and 16 and carry between their outer free ends the transverse bar 75, with the brace bar 76 therebehind. A door 77 is hingedly supported by the bar 75 by the straps 78 and 79 extending from under the outer ends of the door and wrapping around, over and downwardly about the bar.

A center strap 80 is provided to support the center of the door. The door 77 carries a front door 81 hinged thereto along its front edge, the combined doors being sufficient to cover the opening 72 into the hull 27. Along the under side of the front edge of the front door is a lip 82 which enters under the edge of the opening into the hull and prevents the upward swing of the door 81. The rear door 77 may be lifted freely from over the opening 72.

Wooden cam blocks 83 and 85 are fixed to the ends of the hull 27 to project beyond the circumference thereof and are positioned relative to the opening 72 into the hull 27 whereby rotation of the hull will immediately enter the blocks under the rear upturned ends of the straps 78 and 79 to lift the back edge of the door 77 thereby venting the hull before the front door 81 may be opened by reason of the restricting lip 82. Continued rotation of the hull 27, by the crank 63 as above described, will carry the hull around to bring the forward edge of the opening 72 out from over the lip 82 and from under the door 81 whereby the door 81 may then be lifted and swung around upwardly and rearwardly to permit access to within the hull. The blocks 83 and 85 have, upon such rotation, moved around until the door 77 is entirely lifted and spaced upwardly from the surface of the hull, thereby preventing the possible production of sparks from rubbing metal over metal, the blocks being preferably made of wood. The lower edge of the opening 72 is brought around and down to a convenient height over which an operator may work in loading and unloading the cylinder 46.

The cylinder 46 is revolved by the crank 63, as above described, to bring either one of the two doors 69 or 70, here shown as 70, around and under the opening 72 so that the door 70 may be opened outwardly and upwardly therethrough, Fig. 6, to permit access to within the cylinder 46. In order that an operator will not have to put his head into the cylinder to unload it, I provide an unloading platform 86, here shown as built up from slats. On each side of the

platform are two projecting fingers 87 and 88 respectively, Figs. 7 and 8. The platform 86 is inserted through the opening of the door 70 in the cylinder 46 and the fingers 87 on the far side are engaged in notches provided therefor along the edge of the door 69 and under the rib 89. The near edge of the platform is then just above the rib 90 and the fingers 88 extend outwardly therefrom to be received in notches in the lower edge of the door 70, which may then be closed. The cylinder is revolved 180 degrees to bring the door 69 around to the hull opening 72, which action has brought the clothing (not shown) previously under the platform around and on the then top appearing side so that the clothing may readily be reached and pulled over the platform and out the opening 72. Obviously the hull and cylinder may be stopped to provide any angle of slope desired to the platform. Upon unloading, the platform may be removed from the door 69 at once without further rotation of the cylinder.

Referring now to Figs. 9 and 10, in place of employing the intake fitting 34 and the hose 35, fluid may be introduced to spray down over the cylinder 46 to enter the holes 91 therein, by introducing the fluid through a fitting 92 centrally carried between the standards 15 and 16, a length of flexible hose 93, a Y-fitting 94 and the laterals 95 and 96 to the distributing pipe 97 which is substituted for the bar 75 between the arms 73 and 74. Nozzles 98 project from the under side of the pipe 97 through the door 77. Thus, the pipe 97 is raised and lowered with the door 77 by the blocks 83 and 85.

In dry cleaning establishments where volatile grease dissolving fluids are employed, it is a frequent occurrence to have explosions within the hull and many operators have been injured thereby. With my construction, the rear door 77 is always free to be lifted upon an interior explosion, and the blast therefrom is directed rearwardly away from the operator who may be in front of the machine. Furthermore, as above indicated, the front door may not be opened until after the rear has been opened to vent the hull. Chemicals are frequently added to the fluid within the hull while the cylinder is being revolved. As a precaution against injury to the operator during this addition, I provide a filler box 99 on the door 81 having an upper door 100 hinged to the front edge of the box and swinging downwardly and forwardly within the box to open whereby an explosion in the hull will tend to blow the door 100 closed. As an additional convenience to prevent the heretofore necessity of tearing down a machine, I provide a plate 101 over a hand hole in the end of the hull 27 through which wrenches may be inserted to tighten bolts 103 through the flanges 102 supporting the cylinder 46.

While I have here shown and described my invention in the one best form as now known to me, it is obvious that structural changes may be made therefrom without departing from the spirit of the invention, and I, therefore, do not desire to be limited to that form nor any more than may be required by the following claims.

I claim:

1. In a washing machine, a pair of standards, a hull revolvably supported between the standards, a brake means for holding the hull against accidental movement and manually operated means for releasing the brake and means for

- moving the hull when thus released to selective positions.
2. In a washing machine, a pair of standards, a hull revolvably supported between the standards, a cylinder revolvably positioned in the hull, a brake means for holding the hull against accidental movement, manually operated means for releasing the brake and means for moving the hull when thus released to selective position and for moving the cylinder to selective positions relative to the positions of the hull. 10
3. In a washing machine, a pair of standards, a hull revolvably supported between the standards, a cylinder revolvably positioned in the hull, and means for selectively retaining the hull at circumferential points of travel, said hull having an opening therein normally turned upwardly, a cover for said hull opening, and means for holding said cover in a fixed position relative to circumferential movement of the hull. 15
4. In a washing machine, a pair of standards, a hull revolvably supported between the standards, a cylinder revolvably positioned in the hull, and means for selectively retaining the hull at circumferential points of travel, said hull having an opening therein normally turned upwardly, a cover for said hull opening, and means for holding said cover in a fixed position relative to circumferential movement of the hull, said cover having a rear door and a front door hinged in relation to the rear door, and means retaining said front door in a closed position over said hull opening until after said rear door has started to open. 20
5. In a washing machine, a pair of standards, a hull revolvably supported between the standards, a cylinder revolvably positioned in the hull, means for selectively retaining the hull at circumferential points of travel, said hull having a loading opening, a cover for the opening and means supporting said cover to cause said cover to open and direct the exhaust of a blast rearwardly from said opening. 25
6. In a washing machine, a pair of standards, a hull revolvably supported between the standards, a cylinder revolvably positioned in the hull, and means for selectively retaining the hull at circumferential points of travel, said hull having an opening therein normally turned upwardly, a cover for said hull opening, means for holding said cover in a fixed position relative to circumferential movement of the hull, and lip means normally retaining the front end of said cover closed over the front end of said opening whereby said hull is required to be revolved a distance to release said cover retaining lip means. 30
7. In a washing machine, a pair of standards, a hull revolvably supported between the standards, a cylinder revolvably positioned in the hull, and means for selectively retaining the hull at circumferential points of travel, said hull having an opening therein normally turned upwardly, a cover for said hull opening, and means for holding said cover in a fixed position relative to circumferential movement of the hull, the rear end of said cover being free to be lifted upwardly. 35
8. In a washing machine, a pair of standards, a hull revolvably supported between the standards, a cylinder revolvably positioned in the hull, and means for selectively retaining the hull at circumferential points of travel, said hull having an opening therein normally turned upwardly, a cover for said hull opening, and means for holding said cover in a fixed position relative to circumferential movement of the hull, and means for lifting and holding said cover away from the hull during movement of the hull. 40
9. In a washing machine, a pair of standards, a hull revolvably supported between the standards, a cylinder revolvably positioned in the hull, and means for selectively retaining the hull at circumferential points of travel, said hull having an opening therein normally turned upwardly, a cover for said hull opening, and means for holding said cover in a fixed position relative to circumferential movement of the hull, the rear end of said cover being free to be lifted upwardly, and cam means initially lifting the rear end of the cover upon forward travel of the hull. 45
10. In a washing machine, a pair of standards, a hull revolvably supported between the standards, a cylinder revolvably positioned in the hull, and means for selectively retaining the hull at circumferential points of travel and for correspondingly moving the cylinder to bring these door openings together, operated by a common shaft, said retaining means comprising a member frictionally engaging the hull and a lever forcing the member against the hull. 50
11. In a washing machine, a pair of standards, a hull revolvably supported between the standards, a cylinder revolvably positioned in the hull, and means for selectively retaining the hull at circumferential points of travel, a driving gear member for revolving the cylinder, a toothed member on the hull, a rotatable shaft fixed longitudinally, a gear on the shaft in fixed engagement with said toothed member, a crank for revolving the shaft, a gear rotatable on the shaft and slideable thereon into mesh with the cylinder rotating gear, means for connecting the crank and slideable gear to rotate the slideable gear and stop means for holding the slideable gear out of mesh with the cylinder rotating gear. 55
12. In a washing machine, a pair of standards, a hull revolvably supported between the standards, a cylinder revolvably positioned in the hull, and means for selectively retaining the hull at circumferential points of travel, fluid filling means, fluid drain means, overflow discharge means discharging through said fluid drain means for preventing the filling of said hull above a predetermined level and adjustable connections between said hull and said filling means and said hull and said drain means permitting rotation of the hull. 60
13. In a washing machine, a pair of standards, a hull revolvably supported between the standards, a cylinder revolvably positioned in the hull, and means for selectively retaining the hull at circumferential points of travel, a door on each side of said cylinder diametrically opposed one from the other, each of said doors being provided with finger receiving notches in their free outer ends, and a draining and unloading platform detachably mounted in the drum and having fingers projecting from opposite ends of said platform adapted to enter the notches of the doors when the latter are closed, said platform being adapted to be inserted through either of said doors to have the fingers on the far side of the platform enter the notches in the other door then closed and to have the fingers on the near side of the platform be received in the notches of the near door when closed. 65
14. In a washing machine, a pair of standards, a hull revolvably supported between the standards, a cylinder revolvably positioned in the hull, and means for selectively retaining the hull at circumferential points of travel, a pair of doors 70

- on said cylinder diametrically opposed one from the other, each of said doors being provided with finger receiving notches in their free outer ends, and a draining and unloading platform detachably mounted in the drum and having fingers projecting from opposite ends of said platform adapted to enter the notches of the doors when the latter are closed, said platform being adapted to be inserted through either of said doors to have the fingers on the far side of the platform enter the notches in the other door then closed and to have the fingers on the near side of the platform be received in the notches of the near door when closed, and a rib across the cylinder along the side of the opening at each door toward which the free end of the door swings, said fingers on the far side of the platform being below the rib adjacent the closed door, and the fingers on the near side being above the rib at the open door. 15
15. In a washing machine, a pair of standards, a hull revolvably supported between the standards, a cylinder revolvably positioned in the hull, and means for selectively retaining the hull at circumferential points of travel, a pair of arms rockably supported from the standards, a transverse bar between the arms, said hull having an opening therein, a door hingedly connected to said bar and normally resting against the hull across the opening and a cam block carried by and projecting beyond the periphery of the hull adapted to enter under said door upon initial travel of the hull. 25
16. In a washing machine a pair of standards, a hull revolvably supported between the standards, a cylinder revolvably positioned in the hull, and means for selectively retaining the hull at circumferential points of travel, a pair of arms rockably supported from the standards a transverse bar between the arms, said hull having an opening therein, a door hingedly connected to said bar and normally resting against the hull across the opening and a cam block carried by and projecting beyond the periphery of the hull adapted to enter under said door, said door covering the rear part only of said hull opening and being hinged to said bar by its forward end, a second door hinged to the first door adapted to extend forwardly to cover the remainder of said hull opening, and a lip on the under side of the second door adapted to drop down into said hull opening and extend under the forward edge thereof to prevent upward swing of the second door until said hull has been revolved sufficiently to carry the edge of the opening around from over said lip. 35
17. In a washing machine, a pair of standards, a hull revolvably supported between the standards, a cylinder revolvably positioned in the hull, and means for selectively retaining the hull at circumferential points of travel, said hull having an opening therein, a cover for the opening, means for holding said cover stationary circumferentially of the hull during rotation thereof, a pipe across the cover, nozzles extending downwardly therefrom, and a flexible intake conduit leading to said pipe. 45
18. In a washing machine, standards, a hull revolvably supported by the standards, said hull having an opening therein normally turned upwards, a cover for said hull opening in a plurality of separately movable parts, and means for holding said cover in a fixed position relative to circumferential travel of the hull opening, and hinge means connecting the cover with the standards for raising the cover from over said opening. 55
19. In a washing machine, standards, a hull revolvably supported by the standards, said hull having an opening therein normally turned upwards, a cover for said hull opening in a plurality of separately movable parts, and means for holding said cover in a fixed position relative to circumferential travel of the hull opening, and hinge means connecting the cover with the standards for raising the cover from over said opening, and a fluid supply pipe across said cover having openings discharging from the under side of said cover. 65
20. In a washing machine, standards, a hull revolvably supported by the standards, said hull having an opening therein normally turned upwards, a cover for said hull opening in a plurality of separately movable parts, and means for holding said cover in a fixed position relative to circumferential travel of the hull opening, and hinge means connecting the cover with the standards for raising the cover from over said opening, and means automatically lifting said cover at its rear side upon forward rotation of the hull. 90
21. In a washing machine, standards, a hull revolvably supported by the standards, said hull having an opening therein normally turned upwards, a cover for said hull opening having a lip on its forward side, said cover being in a plurality of separately movable parts, and means for holding said cover in a fixed position relative to circumferential travel of the hull opening, and hinge means connecting the cover with the standards for raising the cover from over said opening, the lip means on the forward side of the cover normally engaging the hull opening edge, and means automatically lifting said cover at its rear side upon forward rotation of the hull and before said lip means become disengaged from the hull edge. 100
22. In a washing machine, standards, a hull revolvably supported by the standards, said hull having an opening therein normally turned upwards, a cover for said hull opening in a plurality of separately movable parts, and means for holding said cover in a fixed position relative to circumferential travel of the hull opening, and hinge means connecting the cover with the standards for raising the cover from over said opening, means automatically lifting said cover upon forward rotation of the hull, and a fluid supply pipe carried by the cover movable therewith. 115
23. In a laundry machine, a clothes-containing rotatable cage, a rotatable tub outside of but mounted for rotation concentric with but independently of the cage, means for rotating the cage, means for rotating the tub independently of the cage, a hand-crank and means for operating the cage and the tub rotating means by the crank selectively. 125
24. In a laundry machine, a rotatable clothes-containing cage, a cylindrical casing adapted to hold fluid and concentrically adjacent the cage rotatable about the axis of but independently of the cage, a conduit for conducting fluid from the outside to the inside of the machine, means for rotating the said casing independently of the cage, a member outside of the casing comprising a cover for the top of the casing, said member being fixed against circumferential travel with said casing, and said conduit being mounted in fixed relation with said member. 140
